UNITED STATES PATENT OFFICE.

VICTOR H. EMERSON, OF NEW YORK, N. Y., AND ALEXANDER N. PIERMAN, OF NEWARK, NEW JERSEY, ASSIGNEES TO EMERSON PHONOGRAPH COMPANY, INC., OF NEW YORK, N. Y., A CORPORATION OF NEW YORK.

RECORD-SURFACING AND THE PRODUCTION THEREOF.

1,328,371.

Specification of Letters Patent.

Patented Jan. 20, 1920.

Application filed January 4, 1919. Serial No. 269,663.

To all whom it may concern:

Be it known that we, VICTOR H. EMERSON, of New York city, New York, and ALEXANDER N. PIERMAN, of Newark, New Jersey, have invented a new and useful Improvement in Record-Surfacing and the Production Thereof, which invention is fully set forth in the following specification.

This invention relates to disk records of any type. Among the objects of the invention are: to reduce the weight and thickness of the tablet, and yet to render it less liable to breakage; to reduce the cost of the tablet, without sacrificing the acoustical quality of the record thereon; to expedite the operation of impressing the record-grooves therein; and, in general, to improve the record and the manufacture thereof.

Broadly stated, the invention comprises the employment of a surface-carrier of fabric, and the application thereto of a suitable surfacing, applied in liquid form; a surface-sheet, consisting of fabric thus treated; a tablet having a surface of the character indicated, and having record-grooves on one or both faces thereof; and other features hereinafter set forth and claimed.

The invention will be more readily understood by means of the following description, in which a simple and specific example is set forth as an illustration thereof.

For the surface-carrier, take a piece of woven textile fabric, preferably one which presents a slight nap, such as "sateen", which has been found very satisfactory for this purpose. For the liquid surfacing, take any suitable record-surfacing, such as the ordinary or any desirable record-material, and reduce it to liquid form by the employment of an appropriate solvent or any suitable menstruum. The ordinary record-material is a thermoplastic composition containing finely-ground earthy matter held together by a gum-like binder which usually contains more or less shellac. For acoustical results, the record-surface (with which the reproducing-stylus is to contact) should contain, as is well known, finely-comminuted earthy or gritty matter, and the more shellac it contains the better; and accordingly the practice has sometimes been followed of employing thermoplastic material of high shellac-content as the surfacing-material,

while the body of the disk may contain little or no shellac. All such compositions can be readily reduced to liquid form by a menstruum of alcohol, acetone, or the like, which dissolves the soluble ingredients and carries the unsoluble particles in suspension. In every case, of course, the proper menstruum will be selected with regard to the ingredients of the particular record-surfacing material dealt with.

By adding to such liquid surfacing a toughening-ingredient, such as linseed oil (used as a toughener, in the manufacture of varnishes), the ultimate record-surface is rendered more flexible,—that is, more tenacious and less brittle.

This liquid surfacing, either with or without linseed oil, can be applied to such fabric or carrier in various ways. For example, by flattening out a sheet of the fabric and applying the liquid with a brush; and, if desired, the fabric can then be turned over and the liquid applied to the other side also, to insure thorough impregnation of the fabric (and particularly of the nap-surface) with the liquid menstruum and its surfacing-content. Or, a backing of paper, press-board, or the like, can be taken, and its surface brushed over with said liquid, then a sheet of the fabric flattened out thereon (taking care to have the nap-side uppermost, if there be nap on one side only), and the liquid then applied over the exposed face of the fabric; and, if desired, to the other side of said backing can be similarly applied a second piece of fabric, similarly treated with the surfacing-liquid. Or, a strip of the fabric—or a strip of paper along with the strip of fabric—or a strip of paper between two strips of fabric—can be run through rollers for applying the surfacing-liquid by one operation. Whatever course be followed, the coated or impregnated article is then dried out thoroughly, and until all the volatile content has passed off completely. This seasoning may require from a few hours to several days, according to the nature of the particular menstruum and the particular surfacing-material selected.

After such strip or sheet has become thoroughly seasoned, disks of the required diameter are cut out, ready for the press; or the cutting-out and the impressing can be performed by a single operation of the press,

If the fabric be treated as already-formed disks, there is liability of the edges curling up; whereas, by treating it in the form of a sheet or strip, and not cutting the disks out until the treated fabric has become thoroughly seasoned, more perfect disks are obtained. Where the seasoned disk consists of the built-up layers (comprising paper or the like as well as such fabric), it 5 can be subjected directly to the pressing-matrix, to become (under heat and pressure) a commercial record, single-faced or double-faced as the case may be. Where, however, merely the single sheets of fabric have been 10 surfaced and seasoned, without any backing, then they may be subsequently reinforced, as by a suitable backing (such as paper) interposed between two such carrier-fabrics, or a single sheet of backing can be employed with 15 one carrier-fabric; and, in either case, the layers will become united together, under heat and pressure, simultaneously with the impressing of the record-grooves. This latter is particularly applicable for post-cards, 20 25 "toys", etc.

One manner of carrying out the invention is illustrated by the annexed drawings which are enormously magnified, and not drawn to scale. In these drawings, Figures I and 30 II are sectional views, and Fig. III a perspective on a much smaller scale.

Fig. I shows a brush 4, in the act of applying to the sheet or strip 5, of woven textile fabric, the liquid menstruum 6 that 35 contains suitable record-material in solution or suspension. In Fig. II, said record-material is indicated as the now thoroughly dried-out residuum or surfacing 6', closely adhered to the fabric 5,—no attempt being 40 here made to indicate the depth to which the record-material has penetrated into the fabric. In Fig. III, a knife or other suitable tool 7 is indicated as cutting through the finished sheet 5—6', and around the 45 circle 8, to produce the disk 9.

In these new record-tablets, a minimum of thermoplastic material is employed, which reduces the initial cost; and this material is already spread out into a thin disk, 50 so that a minimum of pressure is required to impart the record-grooves. This dispenses with the necessity of a powerful hydraulic press, and greatly increases the output of the press per hour or per day. The 55 interwoven fibers of the textile fabric act like the steel members in reinforced-concrete structure; and the nap (when present) acts in similar manner, and like the flock used in ordinary thermoplastic record- 60 material. This adds tensile strength to the (very thin) disk as a whole, and binds the surfacing securely into position, as does also the interlocking of the particles of the surfacing with the interwoven fibers of the 65 textile fabric. And the linseed oil (when

used) increases the flexibility and tenacity or toughness of the surfacing, rendering the surfacing-material (and the disk as a whole) less brittle; so that, if the disk should be bent in handling or otherwise, there is little 70 or no tendency to break it or to crock or blister its surface or to mar its record-grooves or to impair the appearance of the record as a commercial article.

The great reduction in the cost of the 75 blank disks, the great increase in the output of the press, the reduction in breakage of the finished records, and the greater economy in shipment (due to the thinness and lightness of the goods), are real advantages 80 which require no elaboration.

The invention is not limited to the precise ingredients and step set forth. It is obvious that many different ingredients are available, that proportions may be varied by 85 the judgment of the manufacturer, and methods and manipulations selected to suit factory conditions, without departing from the spirit of the invention.

The invention having been thus described, what is claimed is:

1. The process of preparing a record-surface, which consists of applying to a fabric a liquid menstruum containing record-material and linseed oil, and drying the same 95 thoroughly and until all the volatile content has passed off completely.

2. The process of preparing a record-surface, which consists of applying to a suitable carrier a liquid menstruum containing 100 earthy matter and a suitable binder therefor and also a toughening-ingredient, and drying the same thoroughly and until all the volatile content has passed off completely.

3. The herein-described record-tablet, having a surface-carrier of fabric, and presenting a surface of earthy matter and shellac and linseed oil.

4. The herein-described record-tablet, having a surface-carrier of fabric, and presenting a surface consisting of record-material and a toughening-ingredient.

5. The herein-described record-tablet, containing a backing or base of suitable material, having a surface-carrier of fabric, and presenting a surface of earthy matter and shellac and linseed oil.

6. The process of preparing a record-tablet, which comprises first treating a sheet 120 of suitable fabric with a liquid menstruum containing record-material, next drying the same thoroughly until the volatile content has passed off, and thereafter cutting out a disk from said treated and seasoned sheet.

7. The process of preparing a record-tablet, which comprises first treating a sheet of suitable fabric with a liquid menstruum containing record-material, next drying the same thoroughly until the volatile content 130

has passed off, and thereafter cutting out a disk simultaneously from said sheet and from a suitable backing united thereto.

8. The process of preparing a record-tablet, which comprises first treating a sheet of suitable fabric with a liquid menstruum containing record-material, next drying the same thoroughly until the volatile content

5 has passed off, and thereafter impressing

a spiral record-groove into the treated and 10 seasoned fabric while simultaneously cutting out from said sheet the disk containing said impressed record.

In testimony whereof we have signed this specification.

VICTOR H. EMERSON.
ALEXANDER N. PIERMAN.
